UNITED STATES PATENT OFFICE.

CARLTON R. RADCLIFFE, OF NEW YORK, N. Y.

HYDRAULIC POWER-TRANSMITTING APPARATUS.

1,121,397.

Specification of Letters Patent. Patented Dec. 15, 1914.

Application filed May 26, 1913. Serial No. 769,942.

To all whom it may concern:

Be it known that I, CARLTON R. RADCLIFFE, a citizen of the United States, and resident of the city of New York, in the 5 county of New York and State of New York, have invented certain new and useful Improvements in Hydraulic Power-Transmitting Apparatus, of which the following is a specification.

10 The present invention relates to improvements in hydraulic power transmitting apparatus of the type disclosed in my pending application for U. S. Letters Patent, Ser. No. 381,342, filed June 28, 1907. In 15 this application a structure is described comprising a primary turbine wheel, in the form of a centrifugal pump impeller, and a secondary turbine wheel, said wheels, in combination with the inclosing casing, being arranged in such a manner that the 20 energy of the liquid developed in the primary wheel is transmitted to and utilized in said secondary wheel, the casing serving to guide the liquid, leaving the secondary wheel, 25 back to the primary wheel, that is to say to the eye of the impeller. It is obvious that in devices of this character the working fluid often attains a temperature which is highly detrimental to the efficiency of the 30 device, and some times rises so high that the operation of the apparatus must be entirely stopped in view of the fact that the general temperature of the mechanism is not substantially below that of the working fluid. 35 It has been proposed heretofore to dissipate the excess of caloric of the working fluid by external means, such as for instance air blowers. It has been found, however, that such devices do not materially reduce the 40 temperature of the working fluid and are, on the other hand, impracticable for the reason that special driving means must be provided.

One of the objects of the present invention is to provide a cooling means for the 45 circulating fluid of a power transmitting apparatus, which means may be identical with the radiator provided for cooling the water circulating in the water jacket around the cylinders of the engine to which the power transmitting apparatus is coupled.

Another object of the invention is to combine the power transmitting apparatus and the radiator in such a manner that both may 50 be filled with liquid through the inlet to the radiator.

With these and other objects in view, which will more fully appear as the nature of the invention is better understood, the same consists in the combination, arrangement and construction of parts hereinafter fully described, pointed out in the appended claims and illustrated in the accompanying drawings, it being understood that many changes may be made in the size and 60 proportion of the several parts and details of construction within the scope of the appended claims without departing from the spirit or sacrificing any of the advantages 65 of the invention.

Two of the many possible embodiments of the invention are illustrated in the accompanying drawings, in which:—

Figure 1 is a front elevation of an internal combustion engine joined with a hydraulic power transmitting apparatus in combination with their common cooling system; Fig. 2 is a vertical central section taken through a hydraulic power transmitting apparatus constructed in accordance with the 75 present invention; and Fig. 3 is a front elevation of a modification of the invention.

Referring now more particularly to Figs. 1 and 2 of the drawings, the numeral 10 indicates an internal combustion engine of any 80 suitable type and construction, its cylinders being shown at 11 and their water jacket at 12. A radiator 13 of any suitable construction is provided, its lower water chamber communicating through a pipe 14 with the 85 water jacket, a suitable pump 15 causing the water to flow from said water chamber to said jacket. A return pipe 16 connects the water jacket with the upper water chamber of the radiator. The parts so far described 90 are well known, their operation and functions being well understood.

The hydraulic power transmitting apparatus comprises a primary turbine wheel 17, in the form of a centrifugal pump impeller, 100 the blades of which are shown in the drawings made integral with an inclosing casing 18, which is attached by screws 19, or otherwise, to the crankshaft 20 of the internal combustion engine. The casing is provided 105 with a heavy external ring 21, acting as the fly-wheel of the engine. Within the casing is disposed a secondary turbine wheel 22, that is to say a turbine rotor having the usual blades. This secondary wheel is carried by a web 22', which is attached by screws 23, or otherwise, to a shaft 24, the 110

latter being shown in the drawings arranged coaxially with the crankshaft 20. The shaft 24 is rotatably journaled in ball bearings 25, which are spaced apart by a sleeve 26, and held in position by the sleeve-like extension 27 of a member 28, which is secured by screws, or otherwise, to the casing 18. In this member are formed passages 29, communicating with a compartment 30 in a stationary bearing part 31, which serves as a further journaling means for the shaft 24. This stationary bearing is connected by brackets 32 with the frame of the internal combustion engine. The passages 29 in the member 28 lead to openings 33 in the casing 18, such openings being disposed in the eye of the impeller. The compartment 30 communicates through a pipe 34 with the lower water chamber of the radiator. In the web 22' are provided near to the outlets of the radial passages of the secondary wheel one or more openings 35, which permit of a flow of the working fluid into a space 37 between the casing and the said web, and thence through a bore 38 in the shaft 24 to a compartment 39 in the bearing 31, the latter compartment being connected by a pipe 40 with the upper water chamber of the radiator. Suitable stuffing boxes 41 and 42 are provided, preventing a leakage of the liquid from the passages in the member 28 and from the compartment 39, respectively. A passage 43 is formed in the member 28, normally closed by a plug 44, said passage leading to the space between the bearings 25 and permitting of the introduction of a suitable lubricant into said space. The shaft 24 is connected, preferably by a universal joint 45, with a shaft 46, the latter being coupled to the part to be rotated.

The operation of this device is as follows: The water jacket of the internal combustion engine, the radiator and the hydraulic power transmitting apparatus are filled with the working fluid through the inlet 47 to the radiator. In operation, when the primary turbine wheel, that is to say the centrifugal pump impeller is rotated, the liquid entering the eye of the impeller, is forced toward the periphery through the radial passages formed in said impeller and enters the vanes of the turbine wheel, causing a rotation of the latter. The liquid leaving the turbine wheel is guided back by the web and casing to the eye of the impeller, to repeat the cycle now described. It is obvious that there is always a partial vacuum at the eye of the impeller, which develops a suction at the openings 33, which are in communication through the passages 29 with the pipe 34. Due to this suction, liquid will be drawn from the lower chamber of the radiator into the impeller. On the other hand, a pressure exists at the opening 35, which will cause liquid to flow into the space 37,

and through the bore 38 and pipe 40 to the upper water chamber of the radiator. From this it will be observed that the centrifugal pump impeller, besides imparting rotation to the secondary turbine wheel, causes a circulation of the working fluid through the radiator, where it is effectively cooled.

A modification of the invention is illustrated in Fig. 3 of the drawings, differing from the one above described in that its pipe 34 is connected with the lower water chamber and its pipe 40 with the water jacket, or in other words the water jacket, the power transmitting apparatus and the radiator form one closed circuit. The water leaving the power transmitting apparatus is forced into the jacket, from there into the radiator, where it is effectively cooled, and drawn from the radiator into the power transmitting apparatus. In the device shown in Fig. 1 of the drawings two circuits are provided, supplied with liquid from a common source of supply, the flow in one circuit being induced by the hydraulic power transmitting apparatus and in the other circuit by the pump 15.

It is obvious that, while herein a specific power transmitting apparatus has been described, any other device could be made use of in connection with the present invention, which lies mainly in the provision of means for causing a circulation of the working fluid through a hydraulic power transmitting apparatus and a suitable cooling means arranged outside of the same, it being possible to insert into this circuit the water jacket of an internal combustion engine which actuates the power transmitting device.

What I claim is:

1. The combination with a hydraulic power transmitting apparatus comprising a casing inclosing two rotatable members, one of said members being adapted to develop a suction at a confined area of said casing and the other one a pressure at another confined area of said casing, of a radiator, a pipe connecting the suction area of said casing with the lower water chamber of said radiator, and a pipe connecting the pressure area of said casing with the upper water chamber of said radiator, said radiator and said power transmitting apparatus being filled with a working fluid, the suction and pressure created in said casing inducing a circulation of said fluid through said apparatus and said radiator.

2. The combination with a hydraulic power transmitting apparatus comprising a casing inclosing a centrifugal pump impeller and a turbine rotor, of a radiator, a pipe connecting the eye of said impeller and the lower water chamber of said radiator, and a pipe connecting the outlet of said tur-

bine rotor with the upper water chamber of said radiator, said radiator and power transmitting apparatus being filled with a working fluid, the rotation of said impeller and said turbine rotor inducing a circulation of said fluid through said apparatus and said radiator.

3. The combination with a hydraulic power transmitting apparatus comprising a casing inclosing a centrifugal pump impeller and a turbine rotor, of a radiator, a pipe connecting the eye of said impeller and the lower water chamber of said radiator, and a pipe connecting the outlet of said turbine rotor with the upper water chamber of said radiator, said radiator and power transmitting apparatus being filled with a working fluid adapted to be poured into the same through the inlet to said radiator, the rotation of said impeller and said turbine rotor inducing a circulation of said fluid through said apparatus and said radiator.
4. The combination with a hydraulic

power transmitting apparatus comprising 25 a casing inclosing a centrifugal pump impeller and a turbine rotor, of a radiator, and a stationary member having two compartments, one of said compartments being connected with the eye of said impeller and 30 the lower water chamber of said radiator, the other one of said compartments being connected with the outlet of said turbine rotor and with the upper water chamber of said radiator, said radiator and power 35 transmitting apparatus being filled with a working fluid, the rotation of said impeller and said turbine rotor causing a circulation of said fluid through said apparatus and said radiator.

Signed at New York, in the county of New York, and State of New York, this 6th day of May, A. D. 1913.

CARLTON R. RADCLIFFE.
